Ernest R. Andis, 3528 N. Bay Drive,
Racine, Wis. 53402

Filed June 1, 1967, Ser. No. 7,321

Term of patent 14 years

(Cl. D34—5)

FIGURE 1 is a perspective view of a golf club head embodying my new design and taken generally from above to the side and from one end thereof, the broken lines indicating a shaft or for illustrative purposes only;

FIGURE 2 is another perspective view of the head shown in FIGURE 1 but on an enlarged scale and with the handle removed;

FIGURE 3 is a side elevational view of the head, but on an enlarged scale from the FIGURE 2 showing;

FIGURE 4 is a perspective view of the head shown in FIGURE 2 but on a further enlarged scale and the view being taken generally from the other side thereof;

FIGURE 5 is a plan view of the head as shown in FIGURE 3;

FIGURE 6 is an elevational view from the side opposite to FIGURE 3;

FIGURE 7 is a bottom view of the head;

FIGURE 8 is an end elevational view; and

FIGURE 9 is an end elevational view from the end opposite to that shown in FIGURE 8.

I claim:

The ornamental design for a golf club head, substantially as shown and described.
